DISHWASHER

William C. Horner, South River, N. J., assignor,
by direct and mesne assignments, of one-third
to George D. Hutchinson and one-third to
T. Milton Matlack, Jamesburg, N. J.

Application August 31, 1933, Serial No. 687,551

4 Claims. (Cl. 299—84)

This invention relates generally to washing devices and has particular reference to devices of that character which are adapted for use in washing dishes or for similar purposes.

5 A principal object of the invention is to provide a device of the kind mentioned which is simple and sturdy in construction and which can be used to wash with soap and then rinse the dishes or other articles. It is so constructed that the 10 amount of soap, or, rather, the proportion of soap in the water, may be varied by manipulating a pair of valves according to the effect desired.

Another object is to provide a construction comprising a novel brush which will permit scrubbing 15 the article to be washed and while supplying either clear water or water containing the desired proportion of soap, thereby facilitating the removal of material which may be adhering too tightly to be quickly removed by the water only.

20 With the foregoing and incidental objects in view, the invention consists in a novel combination and relation of parts, the novel features of which are pointed out in the appended claims, and a preferred embodiment of which is hereinafter described with reference to the drawing accompanying and forming a part of this specification.

In said drawing:

Fig. 1 is a longitudinal section through the device.

30 Fig. 2 is a side view of the device with the casting and some of the interior parts broken away to expose others to view.

Fig. 3 is an end view of the device, with a part 35 of the brush broken away in order to show clearly the construction and relative positions of other parts.

Fig. 4 is a partial top view of the device and shows particularly the relative arrangement of and the captions on the valve buttons.

40 Figs. 5 and 6 are sections on the lines 5—5 and 6—6 respectively in Fig. 2.

The form of the device illustrated in the drawing is adapted to be attached to the hot water faucet of a water supply and used for washing 45 and rinsing dishes, although it may obviously be used for other purposes. It may, of course, be attached to a faucet common to a hot water and a cold water supply so that the temperature and pressure may both be regulated by the faucet valves. The connection is made by means of a 50 hose 10 provided with some means, such as a friction cup 11, for attachment to a faucet. Where separate faucets for hot and cold water are used, the hose may be branched with a separate connection 11 for each faucet if it is desired

to be able to regulate both the pressure and the temperature.

The hose passes through a handle 12 integral with a removable cap 13 which may be held in place by means such as screws 14 on the main shell 15 of the device. The handle 12 preferably is curved so as to afford a convenient grip for holding the device and directing it in use.

5 The hose is attached at 16 to a water conduit 17 which is so constructed as to provide branches 18 and 19 extending through a wall 22. This wall is part of a unit which also comprises walls 23, 24 and 25 which collectively form four compartments 26, 27, 28 and 29. Integral with or attached to the wall 23 is a sleeve 30 which is constructed at its outer end to form a flange 31 fitting closely within the main shell 15. The flange 31 is to support the sleeve against lateral movement with reference to the shell 15.

Opening from the compartment 28 is a passage-way 32 through the wall 23. This opening is to permit water to flow through a soap chamber to what is, for convenience, usually referred to herein as a spray head. This spray head is designated 33 in the drawing. It is screwed on the outer end of a sleeve 34 which fits closely within the sleeve 30 previously mentioned. Loosely mounted within the sleeve 34 is a soap cage 35 which is preferably made of wire mesh or material which is suitably perforated to allow a soap solution to flow readily and still retain a supply of soap until it is dissolved. Mounted upon the cage is a pin 36 or other suitable projection which will permit withdrawing the soap cage for refilling after the spray head 33 is removed.

30 The branch 19 of the water supply extends through the wall 22 and into the compartment 27. The wall 23 is constructed to receive one end of a tube 37 forming an outlet from the chamber 29 and supported in a notch in the flange 31. At its outer end the tube is bent to form a circular ring 38 around the spray head 33. The end 39 of the tube is, of course, closed so that water will be forced through perforations in the spray ring 38. It is obvious, of course, that the spray ring 38 45 may be a continuous one and connected in any suitable way to an open end of the tube 37, but the construction shown in the drawing has certain obvious advantages in the way of manufacture.

50 The flow of the water through the branch 18 or the branch 19, or both, is controlled by a couple of valves in the cross-wall 25. These valves are normally held by springs 39 and 40 in closed position, as shown in Fig. 6, but when the 55

valves are depressed against their springs the valves are unseated and allow water to flow through the compartments 26 and 27 into compartments 28 and 29 opening respectively into the soap chamber passageway 32 and the spray ring tube 31. The valves are provided with buttons 45 and 46 which may be suitably marked to indicate their purpose.

The outer end of the main shell 15 is suitably shaped to receive the spray ring 38 and is also shaped or constructed to provide a seat 47 for a brush ring 48. This brush ring is detachably held in the seat 47 by clips 51. It is preferred to make the brush detachable because it will not always be needed, but when it is needed to remove matter which can not be readily removed by the soapy water there is no difficulty in putting it in position.

In using the device it is connected to the water supply and the soap cage 35 is filled with soap in powdered or other readily soluble form. The water is then turned on and the valve 46 depressed to allow the water to flow through the soap chamber and dissolve the soap. This soapy water is then sprayed upon the dishes or other work with a force depending upon the water pressure, which usually is sufficient to wash dishes or do similar work. However, if it is needed, the brush 48 may be put in place and used to facilitate the washing.

After the soapy water has served its purpose the valve 46 is released and the valve 45 depressed, thereby opening a passageway from the water supply to the spray ring 38 and this spray used for rinsing the dishes.

It is obvious, of course, that the valves may be depressed together if desired, or manipulated so as to vary the proportion of soap in the water delivered from the spray head 33 and spray ring 38. Any operation or manipulation of the valves is made convenient by so placing the valve buttons 45 and 46 that they can be reached by the fingers of the hand on the handle 12.

While the construction shown and described is quite satisfactory in attaining the objects desired, that construction is illustrative only. The construction obviously is capable of variations and changes all coming within the scope of the following claims.

50 What is claimed is:

1. A device of the character described comprising; a connection to a source of water supply; a conduit communicating at one end with said connection constructed to receive a soap

holder and terminating at its other end in a removable spray head; a removable soap holder in said conduit exposed for removal by removal of the spray head; a tube external to said conduit connected at one end to the source of water supply and terminating at the other end in a spray ring disposed circumferentially of the aforesaid removable spray head; and a valve in each conduit operable to open the conduit to permit the passage of water through the conduit associated with the operated valve.

2. A device of the character described comprising a removable spray head provided with a plurality of perforations, a spray ring separate from and curved around the spray head, devices forming independent passages connecting said head and said spray ring to a common source of water supply, the passage to the spray head being constructed to form a soap holding chamber which is rendered accessible for supplying soap by removal of the spray head, a removable soap holding cage in said chamber and a valve in each passage, said valves being operable singly or together to open either or both of said passages to the source of water supply.

25 3. A device of the character described comprising a removable spray head, a spray ring structurally separate from and extending around the periphery of the spray head, devices constructed to form separate passages from the spray head and the spray ring to a source of water supply, the passage to the spray head being constructed to form a chamber under the removable spray head to receive a soap holding cage, a soap holding cage in said chamber, and a compressible valve member equipped with a return spring in each passage, said valves being operable singly or together by the fingers of the hand holding the device to open either or both passages to the water supply and to any extent 40 desired.

4. A device of the character described having a removable spray head provided with a plurality of perforations, a spray ring separate from and curved around the spray head, devices forming separate passages connecting said head and said ring to a common source of water supply, the passage to the spray head being constructed to form a soap holding chamber which is rendered accessible for supplying soap by removal of the spray head, and a valve in each passage operable to open the passage to the water supply.

WILLIAM C. HORNER.
